UNITED STATES PATENT OFFICE.

HUBERT C. ELLIS, OF EVANSTON, ILLINOIS, ASSIGNOR TO ELLIS DRIER & ELEVATOR COMPANY, OF CHICAGO, ILLINOIS, A CORPORATION OF WISCONSIN.

GRAIN-DRIER.

1,331,983.

Specification of Letters Patent. Patented Feb. 24, 1920.

Application filed January 2, 1919. Serial No. 269,366.

To all whom it may concern:

Be it known that I, HUBERT C. ELLIS, a citizen of the United States, and a resident of Evanston, in the county of Cook and 5 State of Illinois, have invented certain new and useful Improvements in Grain-Driers, of which the following is a full, clear, and exact description.

The invention relates to grain driers.

10 One object of the invention is to provide a grain drier which is adapted for installation in one of a series of circular grain bins of usual construction. In recent years, the circular grain bin has gone into use and the 15 present invention provides a grain drier which is adapted for installation in one of such bins.

A further object of the invention is to provide an improved grain drier in which 20 the constituents are arranged so as to minimize friction losses caused by bends and angles in the exhaust and supply passages between the drier and the fan.

The invention consists in the several novel 25 features hereinafter set forth and more particularly defined by claims at the conclusion hereof.

In the drawings: Figure 1 is a side elevation of the improved drier, the grain bin 30 in which the drier is located being shown in section. Fig. 2 is a plan, the bin being shown in section. Fig. 3 is a section taken on line 3—3 of Fig. 4 and Fig. 4 is a vertical section taken on line 4—4 of Fig. 1.

35 The improved drier is illustrated as embodied in one of a monolithic series of grain bins, having an annular surrounding concrete wall 5, a base 6 and a bulk-head 7. The compartment *a* above the bulk-head is 40 adapted to contain a pair of drier sections 8 and the compartment *b* below the bulk-head is adapted to contain a pair of cooler sections 9. These sections may be of any suitable construction, as exemplified by the 45 grain drier set forth in Letters Patent of the United States No. 1,127,964 which is of the vertical shaft type. Each drier and cooler section comprises a series of vertical grain shafts 10 and intermediate transverse 50 inlet flues 11 and outlet flues 12 arranged so that the air will be forced from the inlet flues through the grain shafts 13 and into the outlet flues, the inner sides of said flues being open to the grain shafts. The 55 grain shafts in the drier sections are verti-

cally alined with the shafts in the cooler to cause the grain to flow under usual control from the drier section to the cooler sections. Since the details of these sections form no part of the present invention, further description is not deemed necessary. 60

A characteristic of the drier which adapts it for installation in a circular grain bin is that the sections 8 are convergent so that the aggregate area of the outer ends of the 65 sections and the intermediate air chamber 14 will be less adjacent the circular wall of the bin than the corresponding area at the inner end of the sections, which are located adjacent the center of the bin. An outer 70 wall 15 connects the outer ends of the drier sections and an inner wall 16 connects the inner ends of the sections to form a convergent supply chamber 14 between the drier sections. The cooler sections 9 are 75 correspondingly convergent and corresponding walls 17 and 18 are formed between the sections to form a convergent chamber 19 between them. Louvers 20 in desired 80 number are formed in the annular wall 5 to regulate the escape of air which has passed through the drier sections 8 from the chamber *a* and louvers 21 in suitable number are formed in the wall 5 below the bulk-head 7 to regulate the admission of air into 85 the chamber *b* below the bulk-head from which air is drawn through the cooler sections 9 into the chamber 19.

A fan 22, mounted on the base 6, is disposed in the compartment *b* and is mounted so that its axis will be alined with the center of the chamber 19 between the cooler sections. A suitable inlet trunk 23 leads from the inner side of said chamber to the eye 24 of the fan. This provides a direct 90 passage from the chamber 19. As a result, the air will pass directly from the chamber 19 into the eye 24 of the fan. An outlet trunk 25 is connected to the supply chamber 14 by a duct 26 which extends vertically 100 through the bulk-head 7 and thence horizontally to said chamber 14. The fan outlet 30 is inclined to direct the blast into the duct 26 without sharp bends or corners. A suitable heater 27 is disposed in the duct 26 105 to heat the air supplied to the drier.

In operation, the fan 22 will draw air from the compartment *b* in the bin below the bulk-head through the grain in the cooler sections 9 into the common chamber 110

19 between them and through the trunk 23 and into the eye of the fan. The air thus drawn into the fan will be forced through the duct 26, being heated in transit there-
5 through, into the convergent supply chamber 14 between the drier sections 8 from which the air will be forced through the flues and grain in said sections into the compartment *a* in the bin above the bulk-
10 head.

As the result of the arrangement of convergent chambers between the drier and cooler sections, the apparatus is adapted for installation in a grain bin of usual construction. Another characteristic of this construction is that the fan is disposed so that its eye faces or is opposite the suction chamber 19 and the air is directly discharged into supply duct 26 which is alined opposite the 15 supply chamber 14 and the air is forced through the ducts in such a way as to lessen atmospheric resistance. This arrangement of fan and suction ducts is also of advantage where it is desired to install a grain drier 20 in any place where compact arrangement is desirable. The term "drier" as used herein is to be understood as comprehending a cooler.

The invention is not to be understood as 30 restricted to the details set forth, since these may be modified within the scope of the appended claims, without departing from the spirit and scope of the invention.

Having thus described the invention, what 35 I claim as new and desire to secure by Letters Patent, is:

1. In a grain drier, the combination of 40 a plurality of drier sections having convergent sides, an air chamber between and connected to said sides, and means connected to said chamber for forcing air therethrough.

2. In a grain drier, the combination of a

plurality of drier sections having convergent sides, transverse inlet and outlet flues and grain shafts, an air chamber between 45 and connected to said sides, and means connected to said chamber for forcing air therethrough.

3. In a grain drier, the combination of a plurality of drier sections having convergent sides, a plurality of cooler sections having convergent sides, chambers between said convergent sides respectively, and means connected to said chambers for forcing air therethrough. 50

4. In a grain drier, the combination with an annular inclosing structure, of a drier comprising sections having sides convergent from the center to the outer portion of the structure, an air chamber between and connected to said sections, and means connected to said chamber for forcing air through the sections. 55

5. In a grain drier, the combination with an annular inclosing structure, of a drier 60 comprising sections having sides convergent from the center to the outer portion of the structure, transverse inlet and outlet flues and grain shafts, an air chamber between and connected to said sections, and means 65 connected to said chamber for forcing air through the sections.

6. In a grain drier, the combination with an annular inclosing structure of drier and cooler sections having sides convergent from the center to the outer portion of the structure, a bulk-head in the structure between the drier and cooler sections, an air chamber between and connected to said sections, and means connected to said chamber for forcing air through the drier and cooler sections. 75

HUBERT C. ELLIS.
